VAPOR CONDENSER

Filed Oct. 29, 1942

3 Sheets-Sheet 3

Spec. 2.

A hand-drawn technical diagram of a cylindrical structure, likely a tank or drum, with various internal and external components labeled with numbers 10 through 23. The structure has a flared top and a flared base. Internal components include a central vertical pipe (11) with a horizontal cross-tube (12) and a vertical tube (13) extending downwards. A circular component (15) is attached to the central vertical pipe. External components include a top flange (10) with a valve (6), a side access door (16) with a handle (18), a vertical support (20) with a bracket (21), a base support (22) with a bracket (21), a base support (23) with a bracket (19), and a base flange (8) with a valve (9). Arrows indicate the direction of flow or movement for certain parts.

VAPOR CONDENSER

Karl F. Schoeller, Perkasie, Pa.

Application October 29, 1942, Serial No. 463,807

1 Claim. (Cl. 257—216)

This invention relates to new and useful improvements in vapor condensers and more particularly to a condenser for use in conjunction with high vacuum pumps to prevent water formation in the crankcase of such pumps.

An important object of the present invention is to provide a condenser of the character stated which employs a refrigerant evaporator for the purpose of causing any moisture in the pump line to be absorbed thus preventing passage of said moisture to the vacuum pump proper.

Other objects and advantages of the invention will become apparent to the reader of the following description.

In the drawings:

Figure 1 represents a top plan view.

Figure 2 is a vertical sectional view taken substantially on the line 2—2 of Figure 1.

Figure 3 is a horizontal sectional view taken substantially on the line 3—3 of Figure 2.

Figure 4 is a fragmentary enlarged horizontal sectional view through the evaporator.

Figure 5 is a fragmentary vertical sectional view through the evaporator at the upper portion thereof.

Figure 6 is a fragmentary vertical sectional view through the lower portion of the evaporator.

Referring to the drawings wherein like numerals designate like parts, it can be seen that numeral 5 denotes a tank having a top 6 and a bottom 7. The bottom 7 has a drain plug 8 therein. The lower portion of the side wall of the tank 5 has outlet bosses 9 to accommodate fittings from which lines extend to a pump (not shown). The top 6 has an inlet fitting boss 10 to accommodate a connection to a drier or other machine.

Numerals 11 generally refers to an evaporator which in construction comprises inner and outer spaced walls 12, 13 closed by top and bottom walls 14, 15. The upper and lower portions of this evaporator have hollow headers 16, 17, respectively, defining circular compartments 18 with which connect refrigerant inlet and outlet pipes 19 and 20, respectively. The top and bottom walls 14, 15 have openings 21 therein to communicate the compartments 18 with the space between the walls 12, 13, so that refrigerant can flow from the inlet pipe 19 upwardly through the space between the walls 12, 13 into the compartment 18 at the top of the evaporator and from there to the outlet pipe 20, and return to the compressor (not shown). The evaporator 11 is mounted on suitable webs 22 projecting inwardly from the side wall of the tank.

Suitable legs 23 may be employed for supporting the entire unit.

If desired, the headers 16 and 17 may be constructed integrally with the side walls, by simply extending the side walls 12a, 13a to form the side walls of the headers and then welding or otherwise securing flat rings 30, 31 between the upper and lower portions of the spaced walls 12a, 13a to define compartments 32 corresponding to the compartments 18, the flat rings 31 being formed with apertures 21a to permit flow from the compartments 32 to the space between the intermediate portions of the walls 12a, 13a.

The described vapor condenser is designed to be used in conjunction with a drier operating under a very low vacuum provided by a vacuum pump with the inlet port 10 connected to the drier by a vacuum line. The outlet bosses 9 are designed to be connected to the intake side of the vacuum pump by a suitable line arrangement. The refrigerant is fed into the evaporator by way of inlet pipe 19 and the lower header 15 and under control of a thermostatic expansion valve. The refrigerant is returned by way of outlet pipe 20 to a refrigerant compressor. Refrigerants fed through the lower header 15 are equally distributed throughout the evaporator by means of the openings 21 in said header. The openings 21 in the upper header 14 promote uniform dissipation of refrigerant vapor within the evaporator, thereby preventing possible short circuiting of refrigerants through the evaporator interior. The device is especially adapted for use in vacuum drying processes to absorb moisture and freeze the moisture to the surface of the evaporator, thereby preventing such moisture from passing into the vacuum pump and impairing its efficiency.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

45 A refrigerant evaporator for use in a vapor condenser of the type including a tank having a vacuum inlet and outlet, said evaporator comprising a cylindrical hollow wall structure adapted to be arranged upright in said tank, and annular inlet and outlet headers at the lower and upper ends of said wall structure having perforated walls establishing communication between the headers and the interior of the hollow wall structure, and refrigerant inlet and outlet pipes 50 extending from the inlet and outlet headers and 55 adapted to extend outside said tank.

KARL F. SCHOELLER.
